DOUBLE ACTING SLIDE FASTENER

Millie Cerqua, Bronx, N. Y., assignor to Allen Innovations, New York, N. Y., a partnership

Application November 13, 1936, Serial No. 110,595

7 Claims. (Cl. 24—207)

This invention relates to fastening devices for closing two appropriate members, such as the edges of an opening in a hand bag, a dress, or the like.

5 It particularly relates to fastening devices for the purpose mentioned employing clips slidable along the edges of the opening and secured at spaced points to a flexible member so that when they are crowded towards one end of said opening they release the two edges thereof, and when they are spread out they close the two edges, and my invention has for its main object to provide a device of this character which will be more efficient in operation, and more reliable in its sealing effect than similar devices now in use.

Another object of my invention is to provide a device as characterized hereinbefore the major part of which will be hidden from view and only a comparatively small portion will be exposed 20 on the outside of the article in question, the exposed portion being adapted to add to the artistic appearance of the object to which my invention has been applied.

Still a further object of my invention is to 25 provide a device of this type, in which the individual clips are generally S-shaped, and will be adapted to force the material at the edges of the opening into an overlapping and interlocking relation.

30 Still further objects of this invention will be apparent as the specification of the same proceeds, and among others I may mention: to provide a sliding fastener as characterized hereinbefore which will be simple in construction, inexpensive to manufacture and which will be reversible, that is, it may be used with the flexible member hidden within the article to which my invention is applied or with the flexible member exposed on the outside of said article.

40 In the drawing forming a part of this specification and accompanying the same:

Fig. 1 is a fragmentary perspective view of the upper part of a hand bag showing my invention applied thereto;

45 Fig. 2 is an inside view thereof, the material of the hand bag proper being flattened adjacent to the opening thereof, while

Fig. 3 is a top view under similar conditions as recited with reference to Fig. 2;

50 Fig. 4 is a fragmentary sectional elevation on an enlarged scale, the section being taken on the line 4—4 of Fig. 3, and

Fig. 5 is a similar sectional elevation on the line 5—5 of Fig. 2.

55 Referring now to the drawing more closely by characters of reference, the numeral 10 indicates a lady's hand bag in general, having a right hand wall 11 and a left hand wall 12 made of any appropriate material such as textile fabric.

60 Beads 13 and 14 are formed along the upper edges

of said walls by any appropriate method well known in the art, said beads forming the edges of the opening of the hand bag.

In my invention I provide a plurality of 5 reversely curved or S-shaped sliding clips, generally indicated by the numeral 15, encircling the beads 14 and 13 in the manner indicated in Figs. 4 and 5, and being slidable therealong. That portion of the clip between the two gripping or encircling portions constitutes an intermediate integrating portion which cooperates with each arcuate portion to grip the beads respectively on opposite sides of the integrating portion. It is to be noted that the arcuate gripping portions 10 open substantially toward one another. 15

It is obvious that those portions of the beads 13 and 14 which are embraced by S-shaped clip 15 will be brought into close proximity to one another, completely overlapping to form a nesting or interlocking effect, and will thereby completely 20 close the opening of the hand bag by overlapping the material adjacent thereto, as indicated in all the figures. If the clips 15 are pushed to one side, sliding along the beads 14 and 15, that portion of the beads freed from the clips 15 will be 25 released, permitting the material to be spread apart and the bag opened.

Approximately one-half of the S-shaped clip 15 and only one of the beads will be exposed; in this case the portion indicated by the numeral 30 16 and the outer bead 14. The inner half of the S-shaped clip 15 indicated by the numeral 17, and the bead 13 will be hidden from view.

The exposed half 16 of the bead terminates with a somewhat outwardly curved portion 18 35 snugly but slidably engaging the wall 12 of the bead 14, while the inner half 17 of the S-shaped clip terminates in a circular loop or ring 19 riding on the portion 20 of the other wall 11 of the hand bag adjacent to the bead 18. 40

A flexible cord, chain or other connecting element 21, may be threaded through the rings 19 of the various clips 15, said rings being pressed thereon in such a manner that the clips 15 will be secured on the flexible element 21, preferably 45 equi-distantly.

As it is also usual with such sliding clips, the clip at the one end of said flexible member 21, and of the opening for the bag, will be permanently and not movably secured on the respective 50 beads, while the clip at the other end will be slidable and preferably will be provided with a grip or catch device, indicated by the numeral 22.

When it is desired to open the hand bag, the last slidable clip will be grasped by the device 55 22, and will be pushed towards the fixed clip at the opposite end of the opening of the bag as indicated by the arrow 23, while when it is desired to close the bag the said last sliding clip will be grasped by the device 22 and pulled to- 60

wards the opposite end of the opening of the bag, as indicated by the arrow 24; in both cases carrying with it the flexible member 21 and the rest of the clips 15.

5. As will be understood, the clips 15 will be crowded to one end of the opening when the bag is opened, and they will be spread equi-distantly along said opening when the bag is closed. It is to be noted that loops or rings 19 to which the 10 flexible spacer element is secured are positioned between the overlapped beads. A line drawn approximately through the ends of the two bead-gripping portions of the S-shaped clips passes between the overlapped beads and through the 15 overlapping material adjacent thereto. By this arrangement the pull exerted on each clip by the spacer element when closing the opening is at a point centrally disposed with reference to the beads along which the clips slide. Binding of 20 the clips on the beads is thereby prevented and a very easy closing is insured.

When it is desired, the arrangement of the clips in relation to the flexible member 21 and to the bag may be the reverse, the flexible member 21 being on the outside of the bag. This 25 does not require any change in the construction and operation, merely a reversal of the position of the parts, and it may be used in case bags may be desired to be manufactured with ornamental chains or cords showing on their outsides, along their openings.

It also will be understood that the member 22 by which the last movable clip may be grasped and operated, may be of many other forms as 30 that shown at 22, and such handling or grasping members 22 may be of separate pieces suitably shaped, ornamented, and secured on the respective sliding clip.

While throughout the specification and claims 35 the term "arcuate" has been used to describe the contour of the gripping portions of the clip, it should be understood that this term is intended to embrace structures wherein the contour of each gripping portion is "generally arcuate," and 40 not necessarily a continuous curve. It is obvious that a series of straight portions enclosing successive wide angles might be used in lieu of continuous curves to form substantially the same structure for performing precisely the same 45 functions.

While I have shown and described the preferred embodiment of my invention, I want it to be understood that changes and variations 50 may be made in the construction and combination of the parts, and I want to reserve my rights to such changes and variations as are within the spirit of this specification, and the scope of the claims hereunto appended.

What I claim as new, is:

60. 1. A slide fastener assembly for closing an opening having flexible beads extending along the edges thereof, comprising a series of clips having adjacent generally arcuate gripping portions of reverse curvature joined by a central 65 integrating portion, the outer side of each arcuate gripping portion terminating at a point substantially central with reference to the central integrating portion, and a flexible spacer element secured at spaced intervals along its length 70 to each clip adjacent the extremity of an arcuate gripping portion.

2. A slide fastener assembly for closing an opening having flexible beads extending along the edges thereof, comprising a series of clips 75 having adjacent generally arcuate gripping por-

tions of reverse curvature joined by a central integrating portion, the outer side of each arcuate gripping portion terminating at a point substantially central with reference to the central integrating portion, a flexible spacer element secured at spaced intervals along its length to each clip adjacent the extremity of an arcuate gripping portion, and a pull tab secured to an end clip.

3. A closure for an article having an opening 10 with flexible beads extending along the edges thereof comprising a series of clips each including laterally offset generally arcuate gripping portions of reverse curvature opening substantially towards one another and joined by an intermediate integrating portion cooperable with each arcuate portion to grip said beads respectively on opposite sides of the integrating portion to thereby force said beads and the material immediately adjacent thereto into overlapped 15 relation and maintain the beads in nested relationship when the opening is closed, each clip including at the extremity of each arcuate gripping portion an additional reversely curved portion cooperable with another portion of the clip 20 to slidably receive and guide the material adjacent the respective beads.

4. A slide fastener assembly for closing an opening having flexible beads extending along the edges thereof, comprising a series of clips 25 having adjacent generally arcuate gripping portions of reverse curvature joined by a central integrating portion, the outer side of each gripping portion terminating at a point substantially central with reference to the central integrating portion, and a flexible spacer element secured at spaced intervals along its length to each clip at a point intermediate the gripping portions, each clip including at the extremity of each gripping portion a guide portion cooperable with 30 another portion of the clip to slidably receive and guide the material adjacent the respective beads.

5. A clip for a slide fastener assembly adapted to embrace beads extending along adjacent edges 45 of material comprising adjacent generally arcuate gripping portions of reverse curvature joined by a central integrating portion, the outer side of each gripping portion terminating at a point substantially central with reference to the central integrating portion.

6. A clip for a slide fastener assembly adapted to embrace beads extending along adjacent edges 55 of material comprising adjacent generally arcuate gripping portions of reverse curvature joined by a central integrating portion, the outer side of each gripping portion terminating at a point substantially central with reference to the central integrating portion, and a guide portion at the end of each gripping portion cooperable with another portion of the clip to slidably receive and guide the material adjacent the respective beads.

7. A clip for a slide fastener assembly adapted to embrace beads extending along adjacent edges 65 of material comprising adjacent generally arcuate gripping portions of reverse curvature joined by a central integrating portion, the outer side of each gripping portion terminating at a point substantially central with reference to the central integrating portion, and means positioned adjacent the extremity of one gripping portion 70 for receiving a flexible spacer element.
